No. 769,540.

PATENTED SEPT. 6, 1904.

J. P. GILLETTE.

AUDIBLE INDICATOR FOR ELECTRIC LIGHT OR ELECTRIC MOTOR CIRCUITS.

APPLICATION FILED DEC. 22, 1903.

NO MODEL.

UNITED STATES PATENT OFFICE.

JOSEPH P. GILLETTE, OF NEW LONDON, CONNECTICUT.

AUDIBLE INDICATOR FOR ELECTRIC-LIGHT OR ELECTRIC-MOTOR CIRCUITS.

SPECIFICATION forming part of Letters Patent No. 769,540, dated September 6, 1904.

Application filed December 22, 1903. Serial No. 186,151. (No model.)

To all whom it may concern:

Be it known that I, JOSEPH P. GILLETTE, of New London, in the county of New London and State of Connecticut, have invented a new and useful Improvement in Audible Indicators for Electric-Light or Electric-Motor Circuits; and I do hereby declare the following, when taken in connection with the accompanying drawings and the numerals of reference marked thereon, to be a full, clear, and exact description of the same, and which said drawings constitute part of this specification, and represent, in—

Figure 1, a view in side elevation of one form which my improved audible indicator may assume; Fig. 2, a plan view thereof; Fig. 3, a view of the indicator in vertical central section as constructed for use with alternating currents; Fig. 4, a plan view of the device with its cover removed and also showing it as constructed for use with alternating currents; Fig. 5, a view in vertical central section of one of the modified forms which my improved audible indicator may assume when designed for use in a continuous current; Fig. 6, a plan view thereof with the cover removed.

My invention relates to an improvement in audible indicators for electric-light or electric-motor currents, the object being to produce a simple, compact, convenient, and effective device for calling attention to currents used only a portion of the time and reminding the user to shut them off, such as the currents of incandescent lamps located in cellars or other retired places, the currents of motors not used all of the time, and so on, the device being adapted to be connected in series in such circuits.

With these ends in view my invention consists in an audible indicator having certain details of construction and combinations of parts as will be hereinafter described, and particularly recited in the claims.

As shown in Figs. 1 to 4, inclusive, of the drawings, my invention is embodied in an audible indicator to be used in an alternating electric current. It has a cup-like porcelain receptacle or shell 1, having a base 2 furnished with perforated lugs or ears 3 to re-

ceive the fastening-screws, and a porcelain cover 4, having a centrally-arranged group of holes 5 for the escape of the sound. The said shell is formed at opposite points near its base with oppositely-located lateral openings 55 or holes 6 6, adapting the device to be used for open or outside work, as well as for concealed work, as will be described later on. Upon the top of the shell I place a thin metal diaphragm 7, held in place by a gasket 8, of rubber or equivalent material, upon which the cover 4 rests, as clearly shown in Fig. 3. This diaphragm 7 is vibrated so as to produce what may be described as a "humming" noise by means of a low-resistance magnet 9, through 65 which the alternating current reverses and which is rapidly magnetized and demagnetized thereby, with the effect of attracting and releasing the diaphragm with a rapidity corresponding to the reversals of the alternating 70 current, whereby the diaphragm is vibrated so rapidly as to make a humming noise or signal. The said magnet is located within the shell 1, in which it is supported upon a flat bowed spring 10, situated in the bottom of the 75 shell, which is formed with shallow recesses 11 11 for the reception of the ends of the spring, which is thus prevented from rotating. The core 9^a of the magnet is formed at its lower end with a square shoulder 9^b, which enters a square 80 hole 10^a, formed in the spring, which thus prevents the magnet from turning. An adjusting-screw 12, entered into the shell through a central recess 13 in its bottom, enters the said core 9^a and is employed for adjusting the magnet toward or away from the diaphragm 7, as required, to vary the volume of the sound emitted and to meet the conditions arising from the use of different numbers of lamps in the circuit containing the device. 85 For securing the cover in place I employ two ties 14, having their ends bent at a right angle and secured to the bottom of the shell by means of screws 15. The upper ends of these ties enter grooves 16 16, formed in 90 the upper edge of the shell, and receive screws 17 17 passing through the cover.

The device is provided with two binding-posts, which are connected in the usual way with the magnet 9, and as the shell is adapted 100

by its construction to be used either for open or outside work or concealed or inside work two different kinds of binding-posts are provided. In the drawings I have shown one 5 binding-post of each kind; but it will be understood that in practice a pair of one kind or the other will be used. The binding-post 18, which is the kind provided for outside work, carries at its outer end a binding-screw 19, to 10 which one of the circuit-wires is secured. Its fellow (not shown) has the other wire attached to it. This post 18 has an arm extending through the opening 6 in the shell, to which the post is secured by screws 20 passing up- 15 ward through the bottom thereof. This form of post is best shown in Fig. 5, which is a section taken at a right angle to the section of Fig. 3. For concealed work I employ two binding-posts like the post 21, which is furnished with 20 a hub 22, carrying a screw 23, which holds the concealed circuit-wire entered from the back of the shell into the hub. These screws 23 are operated by a screw-driver inserted through the lateral openings 6. A better view 25 of this binding-post 21 is shown in Fig. 5. It will thus be seen that without modifying the device in itself in any way, particularly the shell, it may be used for outside work or concealed work by simply substituting one kind 30 of binding-post for the other.

The modified form of my device (shown by Figs 5. and 6 of the drawings) is constructed with particular reference to continuous as distinguished from alternating currents. In its 35 general construction the device is like that already described; but in place of the diaphragm 7 I employ a vibrating arm 24, having at its end a contact-point 24^a and forming a part of a strip 25, the lower end of which is 40 clamped under one of the binding-posts. This vibrating arm coacts with a fixed arm 26, carrying a contact-point 26^a and forming a part of a strip 27, clamped under the other binding-post. Under this construction the strip 45 25 and the strip 27, together with the vibrating armature 24, constitute a shunt located between the two binding-posts and providing for the passage of the current around the magnet, so that in the use of this form of the de- 50 vice the current is never broken, as it passes either through the magnet itself or through the shunt. Normally the current between the vibrating arm 24 and the fixed arm 26 is broken. When, however, the current is passed 55 through the magnet 9 the same is energized, and the vibrating arm 24 is attracted and its contact-point 24^a brought into engagement with the contact-point 26^a of the fixed arm 26, whereby a shorter circuit around the magnet is es- 60 tablished between the two binding-posts. The current is then shunted through the shorter circuit and the magnet momentarily demag- netized, allowing the arm 24 to spring away from the arm 26, whereby the shunted circuit 65 is broken and the current goes through the

magnet again with the repetition of the operation described. This operation being rapidly repeated, the action of the vibrating arm produces what I may describe as a "humming" noise, constituting an audible signal. In the 70 form of the device shown by Figs. 5 and 6 it is unnecessary to use the rubber gasket 8.

My improved audible indicator is connected in series in incandescent, electric-light, electric-motor, or other circuits and provides effective means for indicating that the current is on, especially in situations where the current is not used all of the time. Thus one of my indicators placed in the circuit of an electric lamp located in a cellar and designed 75 to be used only a part of the time would attract the attention of the user of the lamp and remind him to turn off the current on returning from the cellar. This illustration will sufficiently suggest the use of the device. 80 85

In view of the modification shown and described and of others which may obviously be made I would have it understood that I do not limit myself to the construction herein set forth, but hold myself at liberty to make such 90 departures therefrom as fairly fall within the spirit and scope of my invention.

Having fully described my invention, what I claim as new, and desire to secure by Letters Patent, is—

95

1. In an audible indicator for connection in series in electric-light or electric-motor circuits, the combination with a shell having two oppositely-arranged lateral openings located near its base, of a cover for the said shell, a magnet located in the shell, a vibrator coacting with the magnet to produce an audible signal, and electric connections leading into and out of the shell through the said lateral openings therein.

100

2. In an audible indicator for connection in series in electric-light or electric-motor circuits, the combination with a shell, of a cover therefor, ties secured to the bottom of the shell and extending upward therein for the attachment of the said cover thereto, a magnet located within the shell, a vibrator coacting with the magnet to produce an audible signal, and connections to and from the magnet leading into and out of the shell.

105

3. In an audible indicator for connection in series with electric-light or electric-motor circuits, the combination with a shell having lateral openings, of a cover for the shell, a magnet located in the shell, a vibrator coacting with the magnet to produce an audible signal, a magnet-supporting spring located in the bottom of the shell, means located in the bottom of the shell for adjusting the magnet with respect to the vibrator against the tension of the said spring, and connections to and from the magnet through the said lateral opening in the shell.

110

4. In an audible indicator for connection in series in electric-light or electric-motor cir-

115

cuits, the combination with a magnet, of a receptacle therefor, a shunt around the magnet including a vibrator coacting with the magnet to produce an audible signal, and electric connections leading into and out of the receptacle, whereby the current passes either directly through the magnet or through the shunt, without being broken.

In testimony whereof I have signed this specification in the presence of two subscribing witnesses.

JOSEPH P. GILLETTÉ.
